UNITED STATES PATENT OFFICE.

CHARLES M. CONLEY, OF CLEVELAND, OHIO, ASSIGNOR OF ONE THIRTY-SECOND TO AMORILUS RODGERS, ONE THIRTY-SECOND TO WILLIAM J. ZANTNER, ONE THIRTY-SECOND TO GEORGE H. FLETCHER, AND ONE SIXTY-FOURTH TO JAMES F. BERANEK, OF CLEVELAND, OHIO.

MILK-BOTTLE AND STOPPER.

No. 830,886.

Specification of Letters Patent.

Patented Sept. 11, 1906.

Application filed December 22, 1905. Serial No. 292,990.

To all whom it may concern:

Be it known that I, CHARLES M. CONLEY, a citizen of the United States of America, residing at Cleveland, in the county of Cuyahoga and State of Ohio, have invented certain new and useful Improvements in Milk-Bottles and Stoppers; and I hereby declare the following to be a full, clear, and exact description of the invention, such as will enable others skilled in the art to which it pertains to make and use the same.

This invention relates to a new and useful improvement in milk-bottles and stoppers therefor.

The object of this invention is to provide a bottle which will be durable, easily cleaned, and which will be securely closed when the stopper is in position.

My invention therefore consists in providing a bottle and stopper which can be cheaply manufactured and having such construction that the stopper will be self-locking when arranged in the neck of the bottle.

My invention further consists in providing a bottle of this character having the seat for the stopper arranged a distance below the rim of the neck, so that the neck portion may be chipped or broken to a considerable extent without affecting the sealing of the jar or bottle.

My invention also consists in the features of construction and combination of parts, as described in the specification, pointed out in the claims, and illustrated in the accompanying drawings.

In the accompanying drawings, Figure 1 is a central vertical section of a bottle embodying my invention with the stopper thereof in position to close the bottle. Fig. 2 shows the stopper.

Again referring to the drawings, 1 represents the body portion of the bottle, which is preferably formed as shown in the drawings, having a comparatively broad base and gradually tapering toward the top, so that the sides are smooth and can be readily cleaned.

2 represents the neck portion, and from the top rim of the neck portion to about half-way down the neck the interior wall thereof is perpendicular, as at 3, and then from the middle portion of the neck the wall slopes in at an obtuse angle to the wall above, so that a seat 4 is formed in the lower part of the neck having outwardly-flaring sides.

The stopper is formed of a more or less resilient material, preferably cardboard, and comprises a flat portion or plate 5, having a diameter approximately equal to the diameter of the neck near its lower end. Around the edge of the plate 5 is formed an outwardly-flaring flange 6, which corresponds to the flaring seat 4. The plate and flange portions are formed from one sheet, preferably by pressing the sheet in a mold, and therefore the tendency of the flange is to flatten out, and the pressure of the flange against the seat 4 locks the stopper in the neck of the bottle. Also when the stopper is on the seat an edge on the perimeter thereof—that is, the upper rim of the flange—will extend into the angle formed by the wall of the seat and the portion of the wall above the seat, and as the tendency of the flange is to flatten out rather than to conform to the vertical wall of the upper part of the neck any cause that would make the stopper move up in the neck of the bottle would force the rim of the flange deeper into the angle, and this further contributes toward keeping the stopper in the bottle.

In order to remove the stopper from the bottle, it is only necessary to engage the flange with a pointed tool, the prong of a fork, or similar article, and the stopper can be readily withdrawn.

It will be seen that as the flange of the stopper fits snugly on the seat in the neck portion a very secure joint is formed, making it impossible for dust to enter or the contents of the bottle to escape.

The arrangement of the stopper near the bottom of the neck of the bottle enables the bottle to be used almost indefinitely, as the chipping of the rim of the neck, which with the present construction of the bottle renders the same worthless, will with my construction not affect the usefulness of the bottle.

What I claim is—

1. The combination with a milk-bottle having an outwardly-flaring seat formed in the neck portion of a stopper comprising a circular plate provided with an outwardly-flaring flange arranged to rest on the seat in the neck of the bottle.

2. The combination with a milk-bottle having an outwardly-flaring seat formed in the neck portion a distance below the rim thereof of a stopper comprising a circular plate provided with an annular outwardly-flaring flange arranged to rest on the seat in the neck of the bottle.

the neck of the bottle, said plate and flange being formed from a single piece of resilient material, substantially as described and for the purpose set forth.

5. 3. The combination with a milk-bottle having an outwardly-flaring seat formed in the neck portion thereof a distance below the rim of the neck, of a stopper comprising a thin circular plate of flexible material, the perimeter of which is beveled downwardly and inwardly so as to rest on the said flaring seat in the neck of the bottle.

4. The combination with a milk-bottle having an outwardly-flaring seat formed in the neck portion a distance below the mouth

of the bottle, the upper surface of the said seat being arranged at an obtuse angle to the wall of the neck portion above the seat, of a flexible stopper arranged to rest on said seat and having an edge on its perimeter extending into the point of the angle formed by the seat and the portion of the wall above the seat, for the purpose set forth. 20

In testimony whereof I sign the foregoing specification in the presence of two witnesses. 25

CHARLES M. CONLEY.
